(57) CLAIM

The ornamental design for a bottle, substantially as shown and described.

DESCRIPTION

FIG. 1 is a front elevational view of a bottle, and the rear elevational view being a mirror image thereof, showing my new design;

FIG. 2 is a right side elevational view thereof, and the left side elevational view being a mirror image thereof;

FIG. 3 is a top plan view thereof;

FIG. 4 is a bottom plan view thereof; and,

FIG. 5 is a front perspective view thereof.

The broken line portions of FIGS. 1, 2, 3, and 5 are included to show unclaimed subject matter only and form no part of the claimed design.
